UNITED STATES PATENT OFFICE.

CHARLES J. BECK, OF PHILADELPHIA, PENNSYLVANIA.

CUTTING AND FOLDING MACHINE.

Application filed July 27, 1925. Serial No. 46,342.

This invention relates to cutting and folding machines for fabrics, of which bags of various descriptions may be made, including heavy burlap potato sacks and cheese cloth interlinings for sugar sacks.

One object of the invention is to provide a compact and efficient machine capable of accurately cutting and folding fabrics of the above noted and extreme characteristics, with equal efficiency.

Another object of the invention is to provide such a machine with adjustable mechanism of a character as will permit of its handling sheets of fabric of a practically unlimited scope of dimensions.

Other advantages and details of construction will be described more fully in the body of the attached specification and are illustrated clearly in the drawings, of which:

20 Figure 1 is a diagrammatic side elevation of the general arrangement of the elements of which the machine is composed;

Fig. 2 is a side elevation of the feeding unit;

25 Fig. 3 is a transverse sectional view, taken on the line 3—3, Fig. 2;

Figs. 4 and 5 are respectively a side elevation, partially in section, and a plan view of the cutting unit;

30 Fig. 6 is a side elevation of the adjusting means for the folding unit;

Fig. 7 is a transverse sectional view taken on the line 7—7, Fig. 6;

Fig. 8 is a sectional elevation taken on the line 8—8, Fig. 7;

Fig. 9 is a sectional plan view taken on the line 9—9, Fig. 8, and

40 Figs. 10, 11, 12, 13 and 14, are diagrams illustrating the various steps in the process of cutting and folding a sheet of fabric.

Fabric such as burlap, of which many commercial containers are made, is a very difficult material to handle by machinery, due to its unreliable quality. It is usually packed in bales for shipment under a heavy hydraulic pressure which causes the folds to adhere to each other, causing considerable difficulty in feeding an automatic machine designed to operate upon it.

50 In Fig. 1 of the drawings, I have illustrated at α a bale of burlap, or other fabric of the same general character, the web γ of which is passing through a machine made in

accordance with my invention, being cut into sheets α and finally folded as at w and stacked for removal from the machine to be stitched or otherwise formed into bags or otherwise converted for use.

The web γ in leaving the bale α is passed under and between loosening bars 1 and 2 which may be supported in any suitable manner. The knife like edges of the bars 1 and 2 separate any folds of the fabric that may adhere to the web γ as it passes into the machine.

From the straightening bars 1 and 2 the web γ passes over guide rolls or bars 3, 4 and 5, all of which tend to cause a resistance to the passage of the web. From the roll 5 the web passes under a roll 6 whose surface is roughened by coating it with granulated material such as emery or the like suitably secured to the surface of the roll by cement or like substance.

From the rough roll 6 the web passes to 75 and over a smooth roll 7, a floating bar or roll 8 being interposed between the rolls 6 and 7 for the purpose of maintaining firm contact between the web and the surfaces of said rolls.

A power driven feed roll 9 engages the web γ , gripping it between itself and the smooth roll 7 and serves to pull the fabric from the bale and feed it to the cutting unit.

The cutting unit comprises primarily a 85 fixed blade 10 and a revolving blade 11. Upon the speed at which the feed roll 9 travels depends the length of the sheet to be cut.

After cutting, the sheet α drops upon a conveyer 12 and is directed to the folding unit, an upper belt 13 overlying and engaging the conveyer to assist in the delivery of the sheet to the folding unit.

The folding unit comprises a fixed jaw 14 secured to a revolving reel and a cooperating 95 movable jaw 15 suitably mounted in said reel. Also in the reel is an adjustable blade 16 whose function is to square the sides of the sheet α with respect to the jaw 14 before the jaw 15 actually contacts therewith, as 100 will be more fully described hereinafter, to complete the folding operation.

In order to insure a positive grip of the fabric sheet α between the jaws 14 and 15, a second revolving reel or cylinder is mounted 105 adjacent the folding reel and is provided

with a pivoted creasing blade 18 which projects beyond the periphery of the cylinder and functions to force the sheet between the said jaws. As the surfaces of the two reels recede, due to their circular movement in opposite directions, the blade 18 is withdrawn, leaving the sheet firmly gripped between the jaws.

The folding reel carries the sheet, in the direction of the arrow (a), Fig. 1, and at a predetermined point of the revolution the jaw 15 is released from the jaw 14, permitting the folded sheet to fall on a stacker platform as at w.

It will be understood that the several units are power driven and timed in such a manner as to feed the desired length of fabric to the cutting unit and at the proper time sever the sheet *x* from the web *y*. The conveyer 12 is so timed with the cutting mechanism as to receive the sheet and deliver it to the folding unit in such a manner as to permit the jaws 14 and 15 to grip the sheet at its centre in order that the sheet may be folded evenly.

Power is supplied to the machine from a suitable source (not shown) through a pinion 20 which meshes with a gear 21 from which a suitable train 22 of interchangeable gears is driven. Meshing with the end gear of the train of gears 22 is a gear 23, to which is secured a mitre gear 24 which, meshing with a second mitre gear 25, drives a shaft 26, to the opposite end of which is secured a mitre gear 27 which meshes with a mitre gear 28, secured to one end of the main drive shaft of the conveyer 12.

The gear 23 drives an intermediate gear 30 which in turn drives a gear 31 secured to the shaft of the feed roll 9.

The pinion 20 also drives a gear 32 which serves to rotate the revolving knife blade 11, and the gear 32 drives an intermediate gear 33 which in turn meshes with a gear 34 which functions to rotate the folding reel. Adjustably carried by the said folding reel and driven therewith is a second gear 35 which meshes with a gear 36 by which the inserting blade 18 is rotated.

A pinion 37 may be caused to mesh with the gear 36 for purposes hereinafter stated, but it normally is out of mesh with said gear and remains in a quiescent state.

It will be noted that the revolving knife blade 11 and the folding jaws 14—15 are geared in such relation as to receive rotary motion at equal speeds.

The feed roll 9 is constructed as clearly shown in Figs. 2 and 3 of the drawings, and comprises a spindle 40 journaled in eccentric bushings 41—41 which in turn are journaled in heads 42—42 on brackets 43—43 secured to the side frames 44—44 of the machine proper. Each of the eccentric bushings 41 is provided with an arm 45, which are connected transversely at their outer ends by a

bar 46. To one end of the bar 46 is secured one end of a spring 47, the opposite end of which is secured to one of the brackets 43, the purpose being to keep the surface of the roll 9 always in firm contact with the surface of the roll 7, the fabric web *y* lying therebetween.

At one end of the spindle 40 is secured a collar 48. Adjacent the collar 48 and splined to the spindle 40 is a flanged sleeve 49 on which is mounted a rubber or other flexible tire 50. Adjacent the tire 50 and recessed to receive the end of the sleeve 49 is a disc 51. The elements 49, 50 and 51 comprise a section, of the feed roll 9, which is duplicated throughout the length of the spindle 40, filling collars 52 being interposed between the sections as shown in Fig. 3.

Adjacent the end of the spindle 40 opposite the collar 48, the said spindle is threaded as at 53, to receive an adjusting collar 54. The collar 54 is split and is provided with a lock screw 55.

Should a slight increase or decrease in the diameter of the feed roll 9 become necessary to feed a slight amount, more or less, of the fabric to the cutting blades, the collar 54 if turned clockwise will compress the rubber tires 50 to such an extent that, due to the inner face and side walls being confined, the outer face of the tire will be expanded, thereby increasing the diameter and the peripheral speed of the feed roll 9. A counterclockwise movement of the collar 54 will act in the reverse to that just described.

Limit screws 56—56 are provided on the levers 45—45 and engage lugs 57—57 on the brackets 43—43, to limit the inward movement of the feed roll 9 toward the roll 7.

The rough roll 6 functions to maintain an even tension upon the web *y* throughout its entire width so that it will not sag at the spaces between the points where the tires 50 of the feed roll 9 engage the fabric and the roll 7.

An apron 60 is pivoted to the brackets 43—43 at 61—61 for the purpose of guiding the web to and over the fixed knife blade 10. A spring 62 tends to keep the apron in contact with a cutter frame 63 which maintains the lower edge of said apron just above the fixed knife blade 10.

The frame 63 is of a substantially U-shaped construction, at the ends of which are provided bearings 64 for a cutter shaft 65. To the connecting leg of the U-shaped frame 63 is secured the fixed blade 10.

Secured to the cutter shaft 65 is a cutter frame 66 comprising a transversely extending flange 67 having three integral arms 68—68 including hubs 69—69 through which the shaft 65 passes. Diametrically opposite the flange 67 is a counterweight 70 formed integral with the arms 68—68. Adjustably secured to the flange 67 is a T-shaped knife

carrier element 71, to which the rotary knife blade 11 is adjustably secured. The construction just described forms a very rigid and substantial frame capable of resisting 5 any abnormal shocks due to overloading of the knife blades such as may occur when a seam in the fabric web y passes through the machine.

It will be noted that the rotary knife blade 11 is set at an angle with respect to the fixed blade 10 so that the blades are actually cutting but a small portion of the web at one time. Due to the continuous movement of the web y over the fixed blade 10 and the 15 fact that the rotary blade does not contact with the fixed blade 10 throughout its entire length simultaneously, provision must be made for correcting the angularity or diamond-shaped cut of the sheet, that would 20 otherwise occur.

For the purpose above stated, the frame 63 is provided with a bracket 72 through which passes a pivot bolt 73, which is secured in a bracket 74 secured to one of the side frames 25 44 of the machine.

For the purpose of correcting the angularity of the cut of the web y , the frame 63 is set at an angle to the longitudinal centre line of the machine and the path of said web. This arrangement provides for the engagement of the lead end of the rotary knife 11 with the fixed blade 10 ahead of the heel end of said rotary knife (Fig. 5) a distance substantially equal to the difference of 30 elevation between the two ends of the rotary knife 11. As an example, should the web be traveling across the fixed blade 10 at a speed substantially equal to the peripheral speed of the rotary knife 11, the sheet will be cut 35 square.

The frame 63 is secured in its adjusted position by bolts 75-75 and 76-76, as shown in Figs. 4 and 5.

It will be noted that the pivot 73 of the frame 63 lies directly in line with the longitudinal centre line of the face of the gear 32, for the purpose of obviating any detrimental effect which may occur between the gear 32 and the pinions 20 and 33 due to misalignment of the teeth of these gears. In 45 Fig. 5, this condition is illustrated in a somewhat exaggerated manner to make this point clear. In practice, the placing of the frame pivot in the described position absolutely 50 prevents any detrimental effect due to this offset condition between the gears, the degree of offset being so infinitesimal.

After the sheet x is severed from the web y , it falls on the conveyer 12, to be delivered to 60 the folding unit, but due to the fact that the sheet is cut from one side to the other progressively, the first cut side tends to travel faster than the last cut side due to the drag by the uncut portion of the web on the partially 65 cut sheet. This condition causes the sheet to

fall on the conveyer at a slight angle with respect to the longitudinal centre line of the conveyer. This condition is corrected in a manner and by mechanism hereinafter described in connection with the folding unit. 70

The folding unit comprises a reel composed of a number of plain faced wheels 80-80 secured to a transversely extending shaft 81 which is suitably journaled in the side frames 44-44 of the machine. At a 75 point on the peripheries of the wheels 80-80 is secured the fixed jaw 14, and adjacent the said fixed jaw 14 said wheels are recessed to accommodate the movable jaw 15. The outermost of the wheels 80-80 are provided with journals for reduced circular ends of said jaw. On one of the said reduced ends, outside the end wheel 80, is secured a lever 82, on one of the arms of which is journaled a cam roller 83 designed to engage alternately a gripping 85 cam 84 and a releasing cam 85, which opens and closes the jaws at the proper time to grip and release a sheet x , respectively. To the second arm of the lever 82 is pivoted a rod 86, between the head of which and a bearing 87, pivoted to the wheel 80, is confined a spring 88 which tends to maintain the jaw 15 in a closed position. 90

Adjacent to and cooperating with the folding reel is a second reel or cylinder which 95 carries the creasing blade 18. The creasing reel is composed of a series of plain faced wheels 90 secured to a transverse shaft 91.

The wheels 90 are recessed to accommodate a pivot bar 92 in which the creasing blade 18 100 is secured. A spring 93 (Fig. 8) tends to maintain the blade 18 in its extended position at all times.

As the folding reel and the creasing reel travel over the top toward the sheet x and the sheet is traveling toward and between the said reels, the creasing blade engages the sheet and forces it back over the upper face of the fixed jaw 14, as the movable jaw 15 is forced open by the gripping cam 84. As 105 the roller 83 rides off the lower end of the cam 84, the jaw 15 closes on the sheet and the blade 18. As the lower portions of the two reels move apart, the blade 18 is withdrawn and the jaw 15 closes tightly on the fabric 110 against the jaw 14. The jaws 14 and 15 having gripped the sheet along its transverse centre line, the folding reel functions to fold the two halves of the sheet together and at the proper time the cam roller 83 engages the releasing cam 85 permitting the jaws to open and allow the folded sheet to fall by gravity to the stacking platform. 115

Previous to the gripping of the sheet at its centre, the squaring blade functions to equalize the two halves of the sheet. 125

The squaring blade 16 is composed of a flat metal bar, rounded on its forward edge and having one end pivoted at 94 to the end wheel 80 of the folding reel, the opposite end be- 130

ing adjustably secured to the other end wheel 80 at 95, the intervening wheels are slotted to accommodate the rear of the blade.

As the forward end of the sheet α passes from the conveyer to and between the folding and creasing reels, the sheet is engaged by the high side of the blade 16 along one edge, thereby drawing the forward corner of the sheet up into transverse alignment with the corner at the opposite side of the sheet, which straightens or squares the sheet at the creasing point with the creasing blade and the jaws 14 and 15. This arrangement assures the four sides of each leaf of the folded sheet being in respective alignment with those of the second leaf of the folded sheet.

The above described operation is diagrammatically illustrated in Figs. 10 to 14, inclusive, of the drawings.

The gear wheel 35 is secured to the shaft 81. The folding reel and the gear wheel 36 are secured to the shaft 91 of the creasing reel. The gear 34 is a ring gear adjustably secured to a centre plate 96 which is secured to the outer end of the shaft 81 of the folding reel. The ring gear 34 is provided with an annular T-shaped groove into which project the head portions of lock bolts 97, the shanks of which project through apertures in the centre plate 96.

In order to adjust the folding and creasing reels that they will grip sheets of various sizes, each one at its respective transverse centre line, the lock nuts 98 of the bolts 97 are backed off, the gear pinion 37 is brought into mesh with the gear 36, and by the use of an adjusting crank 99, (Fig. 6), the two reels are turned through the medium of the gears 37, 36 and 35, until an indicating finger 100 secured to the centre plate 96 is in registry with the dial marking on the ring gear 34, consistent with the length of the sheet about to be cut and folded. Thereafter, the lock nuts are again set and the adjusting gear 37 released from the gear wheel 36.

It will be understood that the ring gear and its intermeshing train of operating gears remain stationary throughout the setting operation.

Obviously the material or fabric may be in the form of a roll, suitably supported, rather than a bale, in which instance the elements of the machine will function in precisely the same manner as described.

I have shown but one form of my invention in the accompanying drawings, but it will be understood that this illustration is merely for the purpose of providing a means whereby, with the assistance of the above specification, the invention may be clearly understood. Modifications of the detailed construction may obviously be made without departure from the essential features of the invention.

I claim:

1. In a cutting and folding machine, a feeding unit; a cutting unit; a folding unit; and means between said cutting and folding units for squaring a cut sheet with respect to 70 said folding unit.

2. In a cutting and folding machine, an adjustable feeding unit; an adjustable cutting unit; an adjustable folding unit; means for receiving a cut sheet from the cutting 75 unit and delivering it to the folding unit; and means for squaring the cut sheet with respect to the folding unit prior to the folding operation.

3. A folding unit for a cutting and folding 80 machine comprising a rotatable folding reel; a fixed jaw on said folding reel; a movable jaw on said folding reel; and a creasing reel comprising a movable blade pivotally mounted in said creasing reel and extending radially from its pivot said blade being cooperative with the fixed and movable jaws of said folding reel.

4. A folding unit for a cutting and folding 85 machine comprising a folding reel and a creasing reel; gripping jaws on said folding reel; a creasing blade on said creasing reel; and means for squaring a sheet of material with respect to said gripping jaws before said jaws and said blade cooperate to 95 grip said sheet of material.

5. A folding unit for a cutting and folding machine comprising a folding reel including a two-part driving element having one part secured to said reel and the second part 100 adjustably secured to the first mentioned part; dial markings on one section of said driving element; and an indicating pointer secured to the other part of said driving element.

6. A folding unit for a cutting and folding machine comprising a folding reel and a creasing reel; gripping jaws on said folding reel; a creasing blade on said creasing reel; and a squaring blade adjustably secured to 110 said folding reel.

7. In a cutting and folding machine, a cutting unit; a folding unit; an endless belt conveyer between said units to receive material from said cutting unit; and an endless belt 115 cooperating with said conveyer at the delivery end thereof to facilitate delivery of said material to said folding unit.

8. The combination in a cutting and folding machine for a continuously moving web 120 of material, of cutting means; means for maintaining a constant and uniform longitudinal tension on said web at all points transversely thereof as the web passes to said cutting means, said cutting means thereby effecting a transversely extending straight line cut from edge to edge of said web and perpendicular to said edges, whereby said web is successively cut into rectangular sheets and each sheet is delivered from said cutting 125 130

means at an angle relative to the line of travel of said web; folding means adapted to engage and fold said cut sheet on a line extending transversely of said sheet and perpendicular to the longitudinal edges thereof; and means for paralleling said angularly disposed sheet with said line of travel prior to being engaged by said folding means.

9. In a cutting and folding machine, the combination of a feeding unit, a cutting unit and a folding unit; said feeding unit being adapted to maintain a web of material under uniform longitudinal tension at all points throughout the width of said web as it is fed to the cutting unit; said cutting unit comprising means whereby the web is cut into rectangular sheets of definite dimensions, the cutting operation starting at one edge of said web and progressing in a straight line transversely to the opposite edge thereof causing the cut sheet to be delivered to the folding unit at an angle with respect to the line of

travel of said cut sheet; means included in said folding unit adapted to effect the folding of said cut sheet along a line extending transversely of said sheet and perpendicular to the edges thereof; and means for squaring the portion of the said angularly disposed sheet which is to be engaged by said fold effecting means relative to said fold effecting means prior to said engagement therebetween.

10. In a cutting and folding machine, rotatable cutting means; rotatable folding means; driving means common to both for causing synchronous rotation thereof; and means for adjusting the said folding means around its center of rotation and relative to the said common driving means whereby the operations of said rotatable cutting and folding means may be caused to register to produce a definite result on a single article.

CHARLES J. BECK.
